Attorney.

UNITED STATES PATENT OFFICE.

RICHARD BERRY PORTER, OF CHILLAGOE, QUEENSLAND, AUSTRALIA.

SEMAPHORE FOR RAILWAY SIGNALING.

1,070,727.

Specification of Letters Patent. Patented Aug. 19, 1913.

Application filed June 14, 1910. Serial No. 566,733.

To all whom it may concern:

Be it known that I, RICHARD BERRY PORTER, a subject of the King of Great Britain, residing at Chillagoe, in the State of 5 Queensland, Commonwealth of Australia, engine-fitter, have invented certain new and useful Improvements in Semaphores for Railway Signaling, of which the following is a specification.

10 This invention relates to illuminated semaphores for railway signaling, and relates particularly to that class of signals in which a hollow box-like swinging or oscillatory arm or blade having a transparent 15 face and lighted interiorly is employed to permit of the use of the semaphore for signaling at night as well as in day time, and it is the object of the invention to provide an improved semaphore of this type which 20 is simple in construction, and durable and efficient in operation.

The improved semaphore consists in constructing the signal-arm in the form of a hollow casing having the greater part of 25 its face covered with a non-combustible transparent material, through which a brilliant light is projected from a suitably disposed lamp or burner located within the said arm. Suitable provision is made for 30 intensifying and directing the light toward the transparent face of the signal-arm, and also for the correct operation of the latter.

In order that the invention may be readily understood, reference will now be had 35 to the accompanying sheet of explanatory drawings, wherein:—

Figure 1 is a perspective view of a signal post fitted with an arm constructed according to the invention. Fig. 2 is a perspective 40 view of the signal-arm drawn to a larger scale. Fig. 3 is a transverse section of the inner end of the said signal-arm. Fig. 4 is a perspective view in horizontal section of the arm shown in Fig. 2, while Fig. 5 is a 45 sectional plan of the same figure.

In these drawings, where like characters of reference have been employed to indicate similar parts in the different views, the numeral 1 designates a signal-post, to the top 50 of which is pivoted a signal-arm (2) of improved construction. This arm (2) is made in the form of a hollow casing, and is constructed of sheet metal, or other preferred material, suitably strengthened by 55 internal stays or hoops (3). If preferred, the said strengthening stays can be placed

on the outside of the arm. The arm (2) is considerably broader at its inner than its outer end, and the former end is covered by a hinged cover or door (4) of approved design for enabling the interior of the said arm to be cleaned, and to provide convenient means whereby the lamp or burner contained therein may receive necessary attention. Any ordinary form of clasp (5) can 60 be affixed to the said door for securing it when closed to the side of the signal-arm. The inner end of said arm (2) is provided with laterally projecting trunnions or journals (6), which form pivotal bearings in a carrying bracket (7) adapted to be bolted 65 to the top of the post (1). One of these journals (6) is bored longitudinally to admit of a gas supply pipe (8) being passed therethrough into the center of the arm, 70 where it is furnished with a suitable burner (9). The said supply pipe (8) is provided with a stop-cock or valve (10), and passes vertically down the side of the post (1) to a gas-producing apparatus (11) of preferred 75 construction.

The major portion of the face of the signal-arm (2) is formed of glass (12) or similar transparent material, through which the rays of light from the burner (9) are projected after being intensified by means of reflectors (13 and 14) located at both ends of the arm. The transparent portion of the face of the said arm can be clear or of any preferred color, and is preferably made in 80 two or more sections or parts, which are retained in position by means of detachable bars (15) or the like. The object in making the transparent portion of the arm in a number of parts, and providing means for securing the same detachably in position, is to 85 enable repairs to be effected economically should part of it be broken from any cause. The interior of the arm (2) can be painted white or given a very high polish, in order 90 to intensify the light from the burner (9), and thereby insure a very strong light behind the transparent portion. The top of the arm is preferably given a curvature, as shown in the drawings, which prevents the 95 settling thereon of water, snow, or other substances blown about by a wind. An air inlet (16) is provided beneath the broadened end of the arm (2), and an outlet (17) is provided immediately above for the escape 100 of the heated atmosphere and waste gas. The said outlet (17) is provided with a 105

curved cover or hood (18) to prevent the ingress of water, snow, or the like to the flame of the burner (9).

In lieu of locating the reflectors (13 and 5 14) in the positions shown in the drawings, they can be positioned against the rear wall of the arm (2), or in positions within the 10 same. Projecting from the inner end of the signal-arm (2) is a short lever arm (19), which is pivotally connected by a link bar 15 (20) to a vertically disposed operating rod (21). The said rod (21) is adapted to be reciprocated vertically by any ordinary means, operated by flexible or other connections, and communicating with suitably disposed controlling levers.

Various means, other than that shown in 20 the drawings, can be readily devised by a fitter or an engineer to pivot the signal-arm (2) on its journals (6).

In order to enable the signal operator to 25 readily determine the exact position of the arm (2), and whether it has responded correctly to the movement of its operating lever, the rear of the said arm is provided with a piece of glass (22) or the like transparent material. Portion of the light within the arm is directed through the said glass (22), and when the arm is lowered the glass 30 is arranged to pass in front of a colored glass or opaque shield (23), secured to the post by a stay or stays (24). Thus, when the arm (2) is in its horizontal or normal 35 position, the signalman will see a clear white light, and when the arm is inclined he will see a colored or no light at all, according as a colored glass or opaque shield (23) is used.

The signal-arm (2) can be illuminated by 40 an ordinary oil lamp, a gas burner, or electric light, and the said arm can be suitably constructed and fitted internally to conveniently accommodate the particular light used. Furthermore, the fittings within the said arm can be so arranged that they will

permit the light to readily adapt itself to 45 the different angles given to the arm. The pivot point of the signal-arm can be at its inner end, as shown, or at its center as is usual at the present time, in which latter case the light would be located at the center 50 of oscillation of the arm.

The operating mechanism at present employed can be used to actuate the improved signal-arm, and the signals will be indicated by placing the arm at the horizontal or incline as hereinbefore set out. At night the 55 arm would be illuminated by its lamp, and the engineer of an approaching train will perceive as readily at night as he could by day the exact position of the arm, and the signal intended to be conveyed thereby.

What I do claim is:—

In a semaphore for railway signaling, the combination with a post, of a hollow signal arm having a transparent face in the front 65 and a transparent portion in the rear near the inner end; a pair of trunnions projecting outwardly from the face and back of said arm whereby it is supported by the post to have up and down oscillatory movement, 70 and one of said trunnions being tubular; an illuminant supplying pipe passing through said tubular trunnion and having a burner within the arm whereby to light the interior of said arm; a reflector at each end of the 75 arm to project the rays of light through the transparent face and transparent portion in the back of the arm; and an opaque shield fixed to the post in such position so that it will project in front of the transparent portion in the back of the arm when the arm is 80 in its lowered position.

In witness whereof I have signed this specification in the presence of two witnesses.

RICHARD BERRY PORTER.
